UNITED STATES PATENT OFFICE.

NICHOLAS MEYERS, OF BUFFALO, NEW YORK, ASSIGNOR TO PETER C. MEYERS, OF BUFFALO, NEW YORK.

PAPER-FEEDING MACHINE.

1,066,133.

Specification of Letters Patent.

Patented July 1, 1913.

Application filed November 3, 1910. Serial No. 590,498.

To all whom it may concern:

Be it known that I, NICHOLAS MEYERS, a citizen of the United States, residing at Buffalo, in the county of Erie and State of New York, have invented new and useful Improvements in Paper-Feeding Machines, of which the following is a specification.

This invention relates to a machine for feeding sheets of paper successively from a pile to a machine which operates on the sheets and more particularly to a machine for feeding small sheets of paper to a printing press for printing circular letters.

The objects of this invention are to provide a machine for this purpose which will operate equally well on all kinds and thicknesses of paper and which can be readily adjusted to feed small or large letter sheets.

In the accompanying drawings consisting of 3 sheets: Figure 1 is a side elevation of my improved sheet feeding machine showing the same adapted for feeding comparatively long sheets. Fig. 2 is a top plan view of the same. Fig. 3 is a vertical transverse section in line 3—3, Fig. 1. Fig. 4 is a fragmentary longitudinal section, on an enlarged scale, in line 4—4, Fig. 2. Fig. 5 is a vertical longitudinal section, on an enlarged scale, in line 5—5, Fig. 2. Fig. 6 is a fragmentary vertical transverse section in line 6—6, Fig. 5. Fig. 7 is a fragmentary horizontal section in line 7—7, Fig. 5. Fig. 8 is a rear elevation of the feeding machine. Fig. 9 is a fragmentary side elevation of the same, partly in section, and viewed from the side opposite to Fig. 1. Fig. 10 is a vertical transverse section in line 10—10, Fig. 2. Fig. 11 is a vertical longitudinal section of the feeding machine showing the same adapted for feeding comparatively short letter sheets. Fig. 12 is a fragmentary vertical longitudinal section in line 12—12, Fig. 2, showing the position of the gage which is engaged by a sheet. Fig. 13 is a cross section in line 13—13, Fig. 12.

Similar letters of reference indicate corresponding parts throughout the several views.

Although the printing press, to which the sheets to be printed are fed by my improved feeding machine may be variously constructed, that shown in the drawings comprises a main frame A, a horizontally reciprocating type bed B guided within the frame and carrying a chase of type b, a

mangle rack C connected by vertically swinging links c, c with the bed so as to move lengthwise therewith and also capable of moving vertically relatively thereto, a driving shaft d provided with a gear pinion d¹ meshing with the mangle rack, a vertically movable ink roller D adapted to engage with the face of the type during the backward movement of the bed and to clear the same during the forward movement of the bed, and an impression roller E adapted to press the letter sheet against the type during the forward movement of the bed and to clear the same during the backward movement of the bed.

Referring to Figs. 1—10, F represents a horizontal table which is adapted to support a pile of sheets f to be printed and which is arranged with its front end adjacent to the rear end of the frame. This table is preferably supported at its opposite longitudinal edges by means of side supporting brackets G which are adjustably connected with the rear end of the press frame in the manner and for the purpose to be hereinafter described.

As the sheets are successively separated from the top of the pile they are received between a pair of coöperating upper and lower horizontal feeding-off rollers H, H¹ and delivered by the latter to the face of the type on the bed. These feed rollers move forwardly on their opposing sides and are turned in unison by engaging these rollers with each other and operatively connecting the same with the driving shaft by means of a belt h passing around a driving pulley h¹ on the driving shaft and driven pulley h² on the shaft h³ of the lower feeding-off roller.

The separation of each uppermost sheet from the next lower sheet of the pile is primarily effected by buckling the upper or top sheet between a buckler and an abutment. The buckler may be variously constructed but preferably comprises a pair of buckling rollers I, I of rubber or other suitable material journaled transversely side by side in bearings on a cross piece i arranged at the front end of a buckling rod J. During the backward movement of the buckling rollers over the top sheet these rollers are free to turn and therefore do not disturb the sheets but during the forward movement of the buckling rollers the same are held against

turning by means of a ratchet wheel l secured to the shaft l^1 of the buckling rollers and a detent pawl l^2 secured to the cross piece and engaging with the teeth of the 5 ratchet wheel, as shown in Figs. 1, 2 and 4.

The buckler is moved forwardly and backwardly over the pile of sheets preferably by means which comprise an upright rear rock lever j arranged in rear of the pile 10 table and having its upper arm pivotally connected with the rear end of the buckler rod J , an upright front rock lever j^1 connected at its upper end to a transverse rock shaft j^2 journaled in bearings j^3 on the underside of the table and having its lower end connected by a front connecting rod j^4 with the mangle gear rack C , and a rear connecting rod j^5 which connects the lower arm of the rear rock lever with the intermediate part of the front rock lever. By this means the buckler is moved forward during the backward stroke of the type bed and vice versa. During the forward movement of the buckler in contact with the top sheet 25 of the pile the front end of this sheet is held against forward movement by an abutment M which bears downwardly against the front end of the pile whereby that part of the top sheet between the buckler and abutment is buckled upwardly and the rear end of the sheet is moved forwardly, as shown in full lines in Fig. 5. After the top sheet has been thus buckled the abutment is raised, thereby permitting the sheet to straighten 30 out and project at its front edge beyond the front side of the pile and between the feeding rollers H , H^1 , whereby the sheet is carried bodily from the pile and delivered upon the type face of the bed which at this time 35 is in its rearmost position ready to receive the sheet. After the sheet has been deposited on the type face the bed advances and carries the sheet under the impression roller E whereby an imprint is produced on the 40 sheet. At the end of the forward movement of the bed the sheet is removed from the type in any suitable manner, so that the type may be inked during the subsequent backward movement of the bed preparatory 45 to receiving the next following sheet. As the top sheet is being carried from the pile the buckler moves rearwardly and after the rear edge of the sheet has cleared the abutment the latter again descends upon the pile 50 preparatory to buckling the next sheet.

Various means may be employed for raising and lowering the abutment those shown in the drawings being preferred and constructed as follows:—The abutment is preferably constructed in the form of a horizontal plate which is provided on its underside with a facing m of rubber or similar material so as to enable the same to obtain a firm grip on the sheet of paper. This plate 55 is secured centrally on its upper side to the

lower end of an upright shifting rod N which slides through an opening formed in the upper overhanging part of a bracket n which is secured to one side of the feed table and also slides through upper and lower eyes n^1 , n^2 of an upward extension of said bracket, as shown in Fig. 10. The abutment is permitted to move vertically but is prevented from turning horizontally by means of a vertical guide rod n^3 secured to the abutment and passing through an opening n^4 in the bracket n . The abutment is pressed constantly downward by a spring o surrounding the shifting rod and bearing at its upper and lower ends against the bracket n and the abutment. The upward movement of the abutment is effected by a tiltable clutch ring p mounted on the shifting rod N above the lower eye n^2 of the bracket n and provided on one side with a laterally projecting pin p^1 , an upright upper link p^2 guided on the bracket n and connected loosely at its upper end with the pin p^1 , a horizontal upper lever Q pivoted transversely on the bracket n and pivotally connected at its inner end with the lower end of the upper link p^2 , a lower upright link g connected at its upper end with the outer arm of the upper lever Q , a lower lever q^1 pivoted lengthwise on the bracket at the side of the feed table and connected at its front end with the lower end of the lower link, and a cam q^2 arranged on the rock shaft j^2 and engaging with a roller q^3 on the rear arm of the lower rock lever. 90

During the last portion of the backward movement of the bed the cam q^2 turns in the direction of the arrow in Fig. 9, which movement is transmitted by the intermediate mechanism to one side of the clutch ring p whereby the latter is tilted and caused to grip the shifting rod N , thereby causing the latter to be lifted and the abutment to be raised from the pile. After the rear edge of the top sheet has cleared the abutment the cam q^2 in its return movement permits the clutch ring p and abutment to descend together until the clutch ring rests on the lower eye n^2 , whereby this ring is permitted to straighten and release itself from the shifting rod N . When this occurs the latter and the abutment are free to continue their downward movement under the action of the spring o independently of the clutch ring until the abutment bears against the top of the pile. By this means the abutment is always lifted the same distance during each operation of the machine but the same is permitted to move downward after each lifting operation until it bears against the top of the pile, thereby automatically compensating for the lowering of the top of the pile as the sheets are fed off successively and enabling the abutment to bear with a practically uniform pressure against the top 110 115 120 125 130

of the pile during each buckling operation regardless of whether the pile is high or low.

If desired, the downward movement of the clutch ring p may be effected solely by gravity but to insure prompt and quick downward movement of the same the action of gravity may be supplemented by a spring P^1 which is arranged around the shifting rod N between the upper guide eye n^1 and the clutch ring p .

When the pile of sheets needs replenishing the abutment and associated parts are lifted the required extent by means of a knob or handle n^5 at the upper end of the shifting rod to permit additional sheets to be placed under the abutment after which the abutment is released and the operation of the machine continues without requiring any readjustment of the parts.

As the abutment rises to permit the buckle in the sheet to straighten out the buckler is effecting the last part of its forward movement and in order to prevent the buckler at this time from interfering with or displacing the top sheet after the latter is within the grasp of the feeding roller, means are provided for lifting the buckler from the pile. The means for this purpose preferably comprise an inclined lifting arm R which projects rearwardly from the center of the abutment and which is adapted to be engaged by the shaft of the buckling rollers between the latter. During the last part of the forward movement of the buckler the shaft of its rollers passes over the lifting arm R , as shown by full lines in Fig. 5, and when the abutment at this time is raised from the sheet the arm thereof also raises the buckling rollers from the sheet, as shown by dotted lines in the same figure.

For the purpose of preventing more than one sheet at a time from being fed off from the pile means are provided comprising a retainer S which is movable vertically toward and from the top of the pile at the rear end thereof. This retainer preferably has the form of a horizontal plate which is provided on its underside with a facing s of rubber or similar material so as to enable the same to obtain a firm grip on the sheets. During the first part of the forward movement of the buckler the retainer is raised so as to permit the rear edge of the topmost sheet to be withdrawn from underneath the retainer and after this occurs the latter is lowered upon the rear end of the second sheet so as to prevent the combing or feeding action of the buckler during the subsequent part of its forward movement from disturbing the second sheet, thereby guarding against feeding two sheets at a time from the pile.

The preferred means for operating the

pile retainer which are shown in the drawings are constructed as follows:— T represents a vertically movable supporting yoke arranged in rear of the feed table and movably supported by a pair of parallel links t, t^1 arranged one above the other underneath the table and pivotally connected at their rear ends with the supporting yoke while their front ends are pivoted to a hanger t^2 depending from the table. The retainer is provided with a rearwardly projecting arm U which is secured by screws u or otherwise with the upper end of the yoke. On its lower part the yoke is provided with an upright slot V in which is arranged an upright lifting rod v which is secured to the yoke. v^1 represents a hanger depending from the rear part of the table and provided with an upright slot v^2 and also with a guide eye v^3 through which the lifting rod v passes, as shown in Figs. 6 and 7. v^4 represents a clutch ring which surrounds the lifting rod v above the eye v^3 and provided with a pin v^5 which projects laterally therefrom into the slot v^2 . W represents a vertically swinging rock lever pivoted on the hanger t^2 and engaging its rear arm with the underside of the clutch pin v^5 while its front arm is adapted to be engaged by a cam w on the rock shaft j^2 , as shown in Figs. 1 and 5.

While the buckler is effecting the first part of its forward stroke and drawing the rear edge of the top sheet from underneath the retainer, the cam w depresses the front arm and raises the rear arm of the lever W whereby the clutch ring v^4 is caused to be first tilted, so as to grip the shifting rod v and then to be lifted with the latter, thereby raising the retainer from the pile through the medium of the yoke and associated parts. After the rear edge of the top sheet has been withdrawn forward from underneath the retainer the movement of the cam w is reversed so as to permit the clutch ring v^4 to descend and rest on the eye v^3 , thereby straightening the latter and disengaging the same from the shifting rod v . The latter and the retainer connected therewith descend with the clutch ring v^4 until this ring is disengaged by its straightening movement from the shifting rod after which the retainer and associated parts continue their descent by gravity independently of the clutch ring v^4 until the retainer rests on the rear end of the pile of sheets. Owing to this construction the retainer is always lifted the same extent but the same is free to move downward after each lifting operation until it bears against the pile, thereby automatically compensating for the lowering of the pile as the sheets are successively carried away from the top of the pile and permitting the retainer to operate uniformly regardless of the height of the pile.

As shown in Figs. 1, 5 and 9, the rear rock lever, *j* and the mechanism which operates the buckler is pivoted on the yoke *T*, whereby the position of this lever is changed 5 simultaneously with the change in position of the buckler and retainer as the surface of the pile of sheets varies, thereby automatically harmonizing the operation of these parts of the machine and avoiding the necessity of manual adjustment for this purpose.

The pile of sheets is held in its proper place on the table by means which comprise a fixed rear gage composed of two sections *x*, *x* secured to the table and engaging with 15 the rear side of the pile and a fixed side gage *x*¹ rigidly secured to the table and engaging with one of the longitudinal sides of the pile and provided with a rubber facing *x*² which 20 engages the adjacent edges of the sheets and assists in holding back the sheets below the uppermost one, so that only the latter is fed off. On its opposite longitudinal side the pile is engaged by a yielding retarding device which operates to prevent more than 25 one sheet at a time from being carried off the pile by the buckler and feed rollers. This retarding device comprises a front presser finger *y* constructed of spring metal and bearing at its inner end inwardly against the 30 front part of the pile of sheets, a rear presser finger *y*¹ also constructed of spring metal and provided at its inner end with a pad *y*² of rubber or similar material which is pressed inwardly against the rear part of 35 the pile of sheets, a longitudinal supporting bar *Y* to which the outer ends of the presser fingers are secured, and means for securing the supporting bar to the table, so that this bar can be adjusted transversely on the table 40 for adapting the tension of the presser finger to the character and size of sheets which are being fed. This adjusting device, as shown in the drawings, preferably comprises an arm *y*³ projecting laterally from the central 45 part of the supporting bar and secured to the table by means of a set screw *y*⁴ passing through a transverse slot *y*⁵ in the arm *y*².

The presser fingers both operate to hold the sheets in place and assist in guiding the 50 same as they successively leave the pile but the rubber pad *y*² of the rear presser finger exerts a retarding effect on the longitudinal edge of the sheets and thus prevents those sheets of the pile below the uppermost one 55 which are not operated upon by the buckler from being carried away with the top sheet, thereby insuring proper feeding of each sheet and preventing the waste which would occur if more than one sheet at a time could 60 be fed off the pile.

Business letters are usually of two sizes, full sheets and half sheets, which are generally known as letters and notes and this feeding machine has therefore been designed 65 to permit of feeding either letters or notes

as desired. When printing either short or long sheets the same are always fed to the printing type, so that the front ends of the sheets arrive at the same place over the type bed or chase so as to enable the sheets to be 70 grasped at the front edges by the sheet delivery mechanism and removed from the type bed after the sheets are printed.

For the purpose of registering the sheets as the same are fed on the type the bed is provided at its front end on opposite sides of the type with front gages. Each of these front gages, as shown in Figs. 1, 2, 12 and 13, comprises a longitudinal arm *B*¹ constructed of a leaf spring which is secured at 75 its front end to the bed and provided at its rear end with upper and lower rearwardly and vertically diverging spring jaws *b*¹, *b*² which yieldingly engage each other. A vertical gage face *b*³ is formed between these jaws by means of a pin arranged on one of these jaws and projecting through an opening in the other jaw. As the sheets are fed by the feeding mechanism over the type of the bed the front edge of the sheet enters 80 between the pairs of jaws of both front gages and against the gage faces thereof and is held frictionally in place while the same is being printed. During the last part of the forward movement of the type bed the 85 front edge of the sheet is engaged between its side edges by the gripper *B*² of a sheet delivery mechanism which first grips the sheet, then moves the same rearwardly out of the jaws of the front gages and then carries the sheet forwardly off from the type bed leaving the latter free to move backwardly and receive the next sheets. This 90 sheet delivery mechanism forms no part of this application and is fully described in an 95 application for patent filed by myself June 10, 1910, Serial No. 566,248.

In order to permit the sheet to be carried forwardly by the gripper *B*² of the delivery mechanism without interfering with the 100 front gages, the latter are depressed from the sheet receiving position shewn in full lines in Fig. 12, to the sheet delivery position shown by dotted lines in the same figure. Each of the gages is held by the resilience of its arm in the normal elevated position and the depression of the same is effected by a presser arm *b*⁴ pivoted on the side of the bed and having a presser finger *b*⁵ which overhangs the gage arm, and a stationary cam *b*⁶ secured to the frame in the path of a laterally projecting lug *b*⁷ on the presser arm. During the last part of the forward movement of the bed the lugs of both presser arms engage with the cams *b*⁶, 115 120 125 whereby the presser arms and gages are depressed after the sheet has been pushed slightly rearward out of the gage jaws by the delivery gripper, thereby permitting the latter during its subsequent forward move- 130

ment to carry the sheet forwardly off the type bed without interfering with the front gages.

As each sheet is fed from the pile table to the type bed the front edge of the same engages under the gripper jaws and is gaged. After the sheet is printed the same is disengaged at its front end from the gage jaws and carried from the type bed either by hand or by automatic means.

When feeding letters or full sheets the mechanism is arranged, as shown in Figs. 1, 2, 5 and 9 in which the feed table is arranged at the rear end of the printing press, the retainer is in its rearmost position and the rod j^4 is connected with the rear part of the mangle gear rack C.

When it is desired to feed note sheets to the printing press the feed table is shifted forwardly on the main frame, so that the short or note sheets will be deposited on the front part of the type bed and with their front edges in engagement with the front gages b^1 . For convenience in permitting the pile table to be thus shifted lengthwise on the frame either in its forward or rearward position, an adjustable connection is arranged between the frame A and the side brackets G which preferably consists of undercut or dove-tail guide ways g formed horizontally and lengthwise on opposite sides of the frame at the rear end thereof and clamping bolts g^1 each of which passes transversely through one of the brackets G and has its head g^2 arranged in the adjacent undercut guideway g and its screw nut g^3 bearing against the outer side of the adjacent bracket G, as shown in Figs. 1 and 3.

When it is desired to shift the pile table lengthwise on the frame for adapting the feed mechanism to long or short sheets, the nuts of the clamping bolts are loosened to permit the same to slide lengthwise in the guideways and after adjustment these nuts are again tightened to hold the parts in position.

It has been found in practice that owing to the length of the long letter sheets the same can be properly fed from the table to the type bed while the table is in a horizontal position but when feeding short note sheets it is desirable to raise the rear end of the pile table, so that the same inclines forwardly and thereby insure engagement of the front edges of the short sheets with the gages b^1 . The preferred means for accomplishing this consists of a cross bar Z preferably of angular form secured to the brackets G in front of the table and feed rollers. In the rearward position of the table when feeding long sheets the cross bar Z engages with its upper horizontal flange z with the top of the frame A while the lower vertical

flange z^1 of this bar engages with the rear end of this frame, as shown in Fig. 5, thereby supporting the pile of long sheets in a horizontal position.

When it is desired to shift the pile table forwardly the same is tilted upwardly, so that the cross bar Z is raised above the frame and the table and associated parts are moved forwardly into the required position for feeding short sheets. While thus moving the table forwardly the cross bar slides with its lower vertical flange over the top of the frame and holds the table in an inclined position when in its foremost position, as shown in Fig. 11, thereby causing the short sheets as they are delivered from the table to engage at their front edges with the front gages b^1 . When the table is thus moved into the forward position on the printing press the connecting rod j^4 is also adjusted accordingly on the mangle rack C by shifting the pivot J^1 which connects the front end of the rod j^4 with the rack C from the rear opening J^2 , as shown in Fig. 1, to the opening J^3 formed in the rack C in front of the opening J^2 . At the same time the pile retainer is shifted forwardly on the table so as to engage with the rear end of the pile of short sheets, as shown in Fig. 11, this being effected by providing the arm U with suitable openings u^1 , u^2 at its front and rear ends for receiving the fastening screws u whereby this arm may be secured to the yoke either in the forward or backward position of the retainer relatively to the table. When feeding short sheets, the rear gages x are also shifted forwardly on the table so as to engage the rear side of the pile and hold the same against displacement.

For the purpose of adjusting the throw of the buckler to suit the character of the paper which is being fed the buckler rod J is provided with a longitudinal row of openings k one or the other of which is adapted to receive a screw k^1 on the upper arm of the rear rock lever j , and the front rock lever j^1 is provided with a vertical row of openings k^2 one or the other of which is adapted to receive a screw k^3 on the front end of the rear connecting rod j^5 , as shown in Fig. 5.

I claim as my invention:

1. A sheet feeding machine comprising a feed table adapted to support a pile of sheets, a buckler adapted to move forwardly over the sheets, an abutment which moves toward and from the pile in front of the buckler, and an operating mechanism for said abutment comprising a shifting rod connected with said abutment, a bracket in which said rod is guided, a tiltable clutch member mounted on said rod, and an actuating member operatively connected with

- said clutch member on one side of the shifting rod and reciprocating lengthwise of the same.
2. A sheet feeding machine comprising a feed table adapted to support a pile of sheets, a buckler adapted to move forwardly over the sheets, an abutment which moves toward and from the pile in front of the buckler, and an operating mechanism for said abutment comprising a shifting rod connected with said abutment, a bracket in which said rod is guided, a tiltable clutch ring arranged on said rod and provided with a laterally projecting pin, and a rock lever operatively connected with said pin.
3. A sheet feeding machine comprising a feed table adapted to support a pile of sheets, a buckler adapted to move forwardly over the sheets, an abutment which moves toward and from the pile in front of the buckler, and an operating mechanism for said abutment comprising a shifting rod connected with said abutment, a bracket in which said rod is guided, a tiltable clutch ring arranged on said rod and provided with a laterally projecting pin, a spring bearing against said ring, and a rock lever operatively connected with said pin.
4. A sheet feeding machine comprising a feed table adapted to support a pile of sheets, a buckler movable forwardly over the sheets, an abutment movable toward and from the top of the pile of sheets in front of the buckler, and means for causing said buckler to rise with the abutment comprising a lifting arm which projects rearwardly from said abutment and with which said buckler is adapted to engage.
5. A sheet feeding machine comprising a feed table adapted to support a pile of sheets, a buckler movable forwardly over the sheets, an abutment movable toward and from the top of the pile of sheets in front of the buckler, and means for causing said buckler to rise with the abutment comprising an inclined lifting arm which projects rearwardly from said abutment and over which said buckler is adapted to engage in the forward position of the latter.
6. A sheet feeding machine comprising a feed table adapted to support a pile of sheets, a buckler movable forwardly over the sheets, a retainer movable toward and from the top of the pile in rear of the buckler, a vertically movable yoke carrying said retainer, a support, and links connecting said yoke with said support.
7. A sheet feeding machine comprising a feed table adapted to support a pile of sheets, a buckler movable forwardly over the sheets, a retainer movable toward and from the top of the pile in rear of the buckler, a vertically movable shifting rod operatively connected with said retainer, a guide for said rod, a tiltable clutch member en-
- gaging with said rod, and a vertically movable actuating member operatively engaging said clutch member on one side thereof.
8. A sheet feeding machine comprising a feed table adapted to support a pile of sheets, a buckler movable forwardly over the sheets, a retainer movable toward and from the top of the pile in rear of the buckler, a vertically movable shifting rod operatively connected with said retainer, a guide for said rod, a tiltable clutch ring arranged on said rod and provided with a laterally projecting pin, and a rock lever engaging with said pin.
9. A sheet feeding machine comprising a feed table adapted to support a pile of sheets, a buckler movable forwardly over the top of the pile and provided with a rearwardly projecting shifting rod, a vertically movable yoke, a rock lever pivoted on said yoke and connected with said rod, and a retainer mounted on the yoke and adapted to engage with the top of the pile of sheets in rear of the buckler for supporting said yoke on the pile.
10. A sheet feeding machine comprising a feed table adapted to support a pile of sheets, a buckler movable forwardly over the top of the pile and provided with a rearwardly projecting shifting rod, a vertically movable yoke, a rock lever pivoted on said yoke and connected with said rod, a retainer mounted on the yoke and adapted to engage with the top of the pile of sheets in rear of the buckler for supporting said yoke on the pile, and means for automatically lowering the yoke and the parts associated therewith as the pile of sheets is reduced.
11. A sheet feeding machine comprising a feed table adapted to support a pile of sheets, a buckler movable forwardly over the top of the pile of sheets, an abutment movable vertically toward and from the top of the pile in front of the buckler, a retainer movable toward and from the top of the pile in rear of the buckler, a yoke carrying said retainer, a lever pivoted on said yoke and operatively connected with said buckler, a transverse rock shaft, and means for transmitting movement from said rock shaft to said yoke, lever and abutment.
12. A sheet feeding machine comprising a feed table adapted to support a pile of sheets, a buckler movable forwardly over the top of the pile of sheets, an abutment movable vertically toward and from the top of the pile in front of the buckler, a retainer movable toward and from the top of the pile in rear of the buckler, a yoke carrying said retainer, a lever pivoted on said yoke and operatively connected with said buckler, a transverse rock shaft, a rock lever on said shaft connected with the rock lever on the yoke, a retainer lever adapt-

ed to lift said yoke, a cam on said shaft engaging with said retainer lever, and means for lifting said abutment comprising a lever operatively connected with the abutment, 5 and a cam on said shaft engaging with the last mentioned lever.

13. The combination with a printing press having a frame and a longitudinally reciprocating type bed, of a feed table 10 adapted to support a pile of sheets, means for feeding the sheets successively from the table over the type bed, and means for supporting the table horizontally in rear of the press frame when feeding long sheets 15 and in an inclined position over the press frame when feeding short sheets.

14. The combination with a printing press having a frame and a longitudinally reciprocating type bed, of a feed table 20 adapted to support a pile of sheets, means for feeding the sheets successively from the table over the type bed, and means for supporting the table horizontally in rear of the press frame when feeding long sheets and 25 in an inclined position over the press frame when feeding short sheets comprising a slidable connection between the front end of

the table and said press frame, and an angular cross bar connected with the table and having a horizontal flange adapted to rest 30 on the press frame and support the table in a horizontal position, and a vertical flange adapted to rest on the press frame and support the table in an inclined position.

15. The combination with a printing 35 press having a frame, a longitudinally reciprocating type bed, a mangle gear rack connected with the bed and a gear pinion meshing with said rack, a feed table adapted to support a pile of sheets, a feeding device for feeding the sheets successively from the table over the type bed, means for adjusting said table lengthwise of the press for feeding different lengths of sheets, and an operating mechanism for said feeding device adapted to be connected with different parts of said mangle rack.

Witness my hand this 21st day of October, 1910.

NICHOLAS MEYERS.
